VAPORIZER

Application filed December 4, 1929. Serial No. 411,484.

Our invention relates to vaporizers, and has for its object the provision of a combined hydrocarbon and air heating vaporizer for automobiles and for such other purposes as it may be adapted to serve. It has for a further object the provision of means for introducing air into the heater chamber of a hydrocarbon vaporizer to reduce or prevent the formation of a vacuum therein. It has for a further object the provision of a novel valve and heater case forming part of said invention. With these and other objects in view, it consists of the structures, combinations and arrangements of parts hereinafter described and claimed.

In the drawings, Fig. 1 is a central vertical longitudinal section partly in front elevation, of our said invention, the hereinafter described fuel or hydrocarbon supply valve being in section and the hereinafter described air intake valve and the hereinafter described heating or vaporizing element being in elevation. Fig. 2 is an exterior side elevation of said invention. Fig. 3 is an exterior front elevation of said invention and Fig. 4 is a top view of said invention.

The hereinafter described fuel supply valve and the hereinafter described air supply valve are preferably similar to each other in construction; it is therefore believed that it will be necessary to describe only one of said valves in detail.

In the drawings, 1 is a casing containing three chambers, as 1^a, 1^b and 1^c, into the central one, 1^b, of which chambers extends an electric heating device, as 2, of any suitable structure. In said chamber 1^a is positioned an electromagnetic valve, comprising a valve seat 3, which is apertured in any suitable manner to permit the outward flow of hydrocarbon fuel therethrough. Said seat preferably embodies an apertured bushing 3^a positioned in the valve aperture of said seat. Said seat is also provided with downwardly directed spacing and guide pins 3^b adapted to extend loosely through suitable apertures in a collar 4^a which encircles a valve stem 4, and to extend into recesses formed in the upper end of an

electric coil spool 5, by which pins said seat and spool are spaced from each other, and within which space said collar may rise and fall.

Said valve stem preferably has formed thereon a shoulder 4^b against which said collar, if loose on said valve stem, is adapted to bear. If desired, however, said collar may be tight on said valve stem, in which case said shoulder may be omitted. Upon said spool is coiled an insulated electric wire 6. Said spool is enlarged at its upper end, and is counter-bored at its upper end to receive one end of a spring 7, which is adapted to bear at its opposite end against said collar to force said valve into closing position against said seat.

The lower end of said valve stem extends into the bore of said spool and is adapted to form the armature of a solenoid or equivalent electro magnet, comprising said coil, spool, core, and a stop 8^a extending into the opposite end of said spool from the lower end of a coil sheath 8, which sheath is pressed over said coil and is adapted to form a ground for any outer turn of the coil from which the insulation may have been abraded in course of assembly or otherwise.

Said coil is preferably wound from one end to the other of said spool and back again, both ends of the wire terminating at or near the same end of the spool. One end of said wire is preferably grounded in any suitable manner on the spool itself and the opposite end is preferably passed through an aperture in the foot of the spool, being insulated therefrom by any suitable sheath or bushing or in any suitable manner, and through an aperture in the lower end of said sheath, being insulated therefrom in any suitable manner, and is electrically connected to a spring contact piece 9 which is adapted to bear against the head of an electric wire binding post 10, adapted to be connected by any suitable means, as by a wire 11, with any suitable source of electricity, as a battery 12. In the circuit of said battery and electro magnet any suitable switch may be interposed, as the switch 13, which may if desired be located on the in-

strument board of an automobile and may be arbitrarily operated by hand.

An outwardly extending boss 16 is formed on the side of said valve casing which is 5 preferably recessed to receive the delivery end of a pipe (not shown) leading from any suitable source of supply of fuel oil under any suitable means of feeding pressure, as gravity. The wall of said casing has 10 formed therein an intake port 16^a leading from the recess in said boss, and adapted to receive a metering screw 16^b which is adapted to govern the amount or rapidity of flow of oil into said casing when said valve 15 is opened.

In like manner a metering screw may be provided for the intake port of the air valve chamber.

It will be observed that said valve seat 20 extends entirely across the chamber in said valve casing so as to cut off any flow of oil between its sides and the wall of said casing, but that there is a slight space between said coil sheath and the side wall of said casing 25 through which oil may flow upward from the intake port in the casing and thence into the space between the head of said spool and said collar, and thence through the pin holes in said collar—or additional holes there- 30 through if desired—and thence around the valve stem in the recess of the valve seat to the discharge port of said valve.

The upper end of said valve casing extends above said valve seat and forms an oil 35 passage 17 communicating with a connecting port 18 extending from said passage 17 through to said chamber 1^a, whence it may flow downward in a space 19 between said heater 2 and its chamber wall and enter the 40 heating element of the vaporizer through an aperture 21 in its side wall. Said heating element may be of any suitable structure.

The operation of the air valve which extends into said chamber 1^a, and the flow of 45 air through it is similar to the operation of the fuel oil valve and the flow of fuel oil through it and we have therefore designated the parts by similar numerals.

In operation, when the switch 13 is closed, 50 the coils of the electro-magnetic valves are energized, thus magnetizing the cores, which attract their valve stem armatures and thus open said fuel-oil and air valves. At the 55 same time, the electric heating element of the vaporizer is energized and electrically heated by means of a parallel circuit including said battery switch and a strap conductor 22. Said heating element is adapted 60 to discharge through its upper end and through a chamber discharge port 23 into the air horn or other sector of the intake manifold of a hydrocarbon internal explosion engine and to supply dense fumes for 65 starting such engine, as is well known to

the art, and is not believed necessary to be further described here.

The upper end of said valve chambers may be closed in any suitable manner or by any suitable means, as by plugs 24, pressed 70 into position.

In operation, one effect of the admission of air through the air valve is to cause a larger volume of vaporized fuel to flow from the heating chamber into the cylinders during the suction strokes of the pistons. Without the air inflow the vaporized charge could not enter the cylinders except by expansion or vapor pressure.

What we claim is—

In a vaporizer, the combination of a heater chamber containing an electric heater; a fuel oil valve chamber provided with an intake port adapted to communicate with a source of hydrocarbon fuel supply, said valve and heater chambers having a port in common through which said valve chamber may discharge hydrocarbon fuel into said heater chamber; an electro-magnetic valve positioned between the intake and discharge ports of said fuel oil chamber and adapted to govern the flow of hydrocarbon fuel to said heater chamber; an air valve chamber provided with an intake port communicating with the atmosphere, said air valve chamber and said heater chamber having a port in common through which said air valve chamber may discharge air into said heater chamber; an electro-magnetic valve positioned between the intake and discharge ports of said air valve chamber and adapted to govern the flow of air to said heater chamber, said heater chamber having a discharge port formed therein adapted to discharge heated and vaporized hydrocarbon fuel and fumes from said heater chamber, and electric means for energizing said valves and for independently energizing said heater and adapted to open said valves when said heater is in operation.

In testimony whereof, we hereunto affix our signatures.

IRVING E. ASKE.
